Primary Examiner — Melanie Pellegrini(74) *Attorney, Agent, or Firm* — Stephen Kenny; Peter Sullivan; Foley Hoag LLP(57) **CLAIM**

The ornamental design for a ring, as shown and described.

DESCRIPTION

FIG. 1 is a front perspective view of the ring;

FIG. 2 is a front view thereof;

FIG. 3 is a back view thereof;

FIG. 4 is a front and left side perspective view thereof;

FIG. 5 is a bottom view thereof;

FIG. 6 is a top view thereof;

FIG. 7 is a left side view thereof; and,

FIG. 8 is a right side view thereof.

The broken lines shown in the drawings represent portions of the ring which form no part of the claimed design.
